UNITED STATES PATENT OFFICE.

HORACE J. FARRAR, OF SEATTLE, WASHINGTON, ASSIGNOR TO UNIVERSAL HIGH POWER TELEPHONE CO., OF KING COUNTY, WASHINGTON.

DESIGN FOR AN INDIRECT-LIGHTING FIXTURE.

52,641.

Specification for Design.

Patented Nov. 12, 1918.

Application filed September 13, 1916. Serial No. 119,986. Term of patent 7 years.

To all whom it may concern:

Be it known that I, HORACE J. FARRAR, a citizen of the United States, and a resident of Seattle, in the county of King and State of Washington, have invented a new, original, and ornamental Design for Indirect-Lighting Fixtures, of which the following is a specification, reference being had to the accompanying drawing, forming a part thereof.

In the drawings, numeral 1 indicates the ceiling fixture of a light. 2 indicates the light globe.

I claim:

The design for an indirect lighting fixture as shown.

HORACE J. FARRAR.
